Abel L. Brownrigg

UNITED STATES PATENT OFFICE.

NICOLA J. SERAPHINE, OF NEW YORK, N. Y.

TOY.

1,369,556.

Specification of Letters Patent. Patented Feb. 22, 1921.

Application filed April 26, 1918. Serial No. 230,883.

To all whom it may concern:

Be it known that I, NICOLA J. SERAPHINE, a citizen of the United States, residing in New York, in the county and State of New 5 York, have invented certain new and useful Improvements in Toys, of which the following is a specification.

My invention relates generally to toys and particularly to toys of the general type in 10 which balls are caused to roll along runways into engagement with suitable target devices.

In devices of this general nature heretofore known and used a complicated mechanism has invariably been made use of that rendered the toys unsuited for use by very 15 young children. As an instance, one objectionable feature that has usually appeared involves the use of resetting devices 20 after each operation to place the apparatus in condition for a following operation. The principal object of the present invention is accordingly to provide a simplified toy of the general type referred to that can be 25 manipulated by very young as well as by children of more advanced years.

With this and other objects in view, one 30 feature of the invention consists in the provision of a toy having an inclined runway and a pivoted figure mounted in such relation to the runway as to be rocked about its pivot by a ball rolling down said runway, and means for automatically bringing said 35 figure back to its normal position after an operation.

Another feature of the invention consists in the provision of means whereby the toy may be readily taken apart and folded together for convenience in packing.

40 In the drawings,

Figure 1 is a view in perspective of a device embodying the invention in a preferred form.

Fig. 2 is a transverse vertical sectional view of the device taken along the line 2—2 45 of Fig. 1.

Fig. 3 is a fragmentary detailed view showing a pivotal mounting for a portion of the device.

50 Fig. 4 is a view taken transversely to the view shown in Fig. 3.

Fig. 5 is a fragmentary sectional view showing a detachable connection for the supporting standards.

55 In Fig. 1 of the drawing there is shown in

perspective a view of an embodiment of a preferred form of the invention in which the trough-shaped runway 1, formed preferably of sheet metal, is mounted on removable legs or standards 2 at such an inclination to the 60 horizontal that a ball 3 placed on the runway at its higher end will roll swiftly along the concave surface thereof through the action of gravity. In order to add to the interest of actuating the toy and to furnish 65 an additional object for causing the ball to roll down the runway, I preferably provide a target or figure such as is indicated at 4 and which is mounted in a suitable position opposite the lower end of the runway, where 70 it will be engaged by the ball as it is projected from the end of the runway 1 by the momentum acquired in its descent.

The figure 4, which is shown in this instance as representing a clown holding a 75 baseball bat, is preferably pivotally mounted so that the figure is rocked backward about the pivots 5 placed in positions coinciding with the heels of the figure. In order to prevent the figure from tilting backward 80 beyond a certain predetermined angle, stop lugs 6 are preferably provided which are adapted to engage the support 7 on which the figure is mounted to thereby define one of the limits of movement for the figure, as 85 will be obvious. Not only are means provided for limiting the extent of tilting of the figure, but I also provide means for causing the figure to assume its normal upright position when the force of impact of the 90 striking ball has been dissipated. This means preferably takes the form of grotesque feet 8 with which the figure 4 is provided and which are formed of lead or other comparatively heavy material. It will be 95 seen that the weighted feet 8 are arranged to project to such an extent to the front of the figure that they will exert a substantial tendency to bring the figure back to its normal position from any position to which it 100 may have been deflected. While the particular means shown for returning the figure to its normal position is adequate for the purpose in view, it will be obvious that other means widely differing from the particular 105 ones shown may be employed for biasing the figure to its upright position.

The support 7 for the figure 4, to which reference has already been made, is preferably formed by a runway similar in most 110

respects to the runway 1, except that it is placed at such an inclination to the horizontal that a ball will roll along the pathway formed by it in a direction opposite the direction of movement of a ball rolling along the upper runway 1. As will be seen the runway 7 is suspended beneath the upper runway 1 by means of the chains or other flexible members 9 so as to provide a return path 10 for a ball that has traversed the length of the upper runway 1 and has rebounded from contact with the target figure 4. Not only do the chains 9 serve to support the lower runway 7 beneath the upper runway 1 in position to receive a ball that has rolled down the upper runway, but the flexible means of suspension provides also for obtaining a slight impulse or throw on the part of the lower runway 7 and the figure 4 carried by it as the full impact of the ball is received by the figure. The swinging impulse thus imparted to the lower runway as the ball strikes the figure adds to the interest of a child in the toy and enhances its 25 attractiveness.

Still another purpose served by providing flexible supports for the lower runway resides in the provision which is thus made for folding the toy into a small space to 30 facilitate its packing for shipment or any other purpose. A further extension of this idea resides in the provision of tubular sockets 10 in which the upper ends of the standards 2 are held and from which the standards 35 can be readily removed when it is desired to dismount the device for packing or the like.

Preferably horizontally arranged chain members 11 serve to prevent the lateral 40 spreading of the standards 2 and one of these members is so placed above the lower end of the return runway as to provide a support for a suitable bell 12 which is thereby placed in the path of the returning balls 45 to be engaged and sounded thereby. A receptacle such as 13 may be placed at the delivery end of the return runway in which to receive the balls if desired.

It will be seen from the foregoing 50 description that a toy has been produced that is particularly designed to furnish amusement to very young as well as to children of more advanced years. A set of three of the balls would ordinarily be provided 55 which may be colored red, white and blue respectively, and the action of each ball as it rolls down the upper runway to be apparently struck by the waiting batsman and then roll down the return path provided by 60 the lower runway and strike the suspended bell before it drops from the end of the run-

way, is such as to afford the keenest delight to a child.

Having thus described my invention, what I claim and desire to secure by Letters 65 Patent of the United States, is:—

1. A toy comprising: an inclined runway, a support therefor, a runway mounted beneath said first named runway and inclined in the opposite direction, one end of the 70 lower runway extending beyond the adjacent end of the upper runway, and a figure mounted on the extended end of the lower runway, whereby a ball rolled down said upper runway will strike said figure and be 75 deflected thereby into the return path afforded by said lower runway.

2. A toy comprising: an inclined runway, a support therefor, a runway mounted beneath said first named runway and inclined 80 in the opposite direction, one end of the lower runway extending beyond the adjacent end of the upper runway, and a figure pivotally mounted on the extended end of the lower runway opposite the end of the 85 upper runway, whereby a ball rolled down said upper runway will strike said figure and rock the same about its pivot, and means for 90 rocking the figure back to its normal position.

3. A toy comprising: an inclined runway, a support therefor, a second runway suspended from said first named runway and inclined in the opposite direction, the higher 95 end of the lower runway extending beyond the adjacent lower end of the upper runway, and a buffer member on the extended end of the lower runway, whereby a ball rolled along said upper runway will strike said buffer member and swing said second runway out of its normal position and be deflected by said buffer member into said 100 second runway.

4. A toy comprising: an inclined runway, a support therefor, a second runway suspended from said first named runway and inclined in the opposite direction, a bell mounted adjacent the lower end of the second named runway, the higher end of the lower runway extending beyond the adjacent lower end of the upper runway, and a figure pivotally mounted on the extended upper end of the lower runway, whereby a ball rolled along said upper runway will strike said figure to tilt the same about its axis and 110 also be deflected by said figure into the return path afforded by said lower runway and into engagement with said bell.

Signed at New York, in the county and State of New York, this 15 day of April, 120 1918.

NICOLA J. SERAPHINE.
